R. E. KEOUGH

TRACK GAUGE

Filed April 16, 1926

UNITED STATES PATENT OFFICE.

ROBERT EMMET KEOUGH, OF MONTREAL WEST, CANADA, ASSIGNOR TO THE AMERICAN FORK & HOE COMPANY, OF CLEVELAND, OHIO, A CORPORATION OF OHIO.

TRACK GAUGE.

Application filed April 16, 1926. Serial No. 102,568.

My invention relates to improvements in railway track laying tools and more particularly to track rail gauges.

An object of the invention is to provide for accurately spacing railway rails parallel to each other.

Another object of my invention is to provide a rail gauge tool by the use of which base spacing of the rails may readily be accurately accomplished by gauging the spacing of the bases of the rails.

Another object of my invention is to construct a rail gauge which is simple in construction, cheap to manufacture and which is durable.

Other objects and advantages of my invention will be apparent by reference to the accompanying specification and drawings, forming a part thereof, wherein I have shown several embodiments of my invention.

Referring to the drawings:

Fig. 1 shows an elevation of one embodiment of my invention in use;

Fig. 2 shows a plan view of the same;

Fig. 3 shows a sectional view of one form of the rail flange contact and the retaining means therefor;

Fig. 4 shows a plan view of another embodiment of my invention;

Fig. 5 shows a top plan of the same after formation;

Fig. 6 shows an elevation of still another form of rail flange contact;

Fig. 7 shows a top plan view of the same;

Fig. 8 shows an elevation of a modified form of rail and base flange contact;

Fig. 9 shows a side elevation of another embodiment of my invention with one of the contacts shown in section;

Fig. 10 shows a top plan view of the same; and

Fig. 11 shows an end elevation of the contact.

Referring now to all of the figures of the drawings, in which like parts are designated by like reference characters, 1 designates a stock or body of my base rail gauge preferably formed of a rectangular rod of mild steel and adapted to support at one end thereof a head and base flange contactor 2 and at the opposite end thereof, a base flange contactor 3. The contactors 2 and 3 are preferably secured to the stock 1 by means of nuts and bolts 14 and 15, and 22 and 33 and plates

8 to 13 are interposed between the stock 1 and the said securing means. A handle 4 is preferably provided and secured in any suitable manner to the stock 1, the handle effecting better manipulation of the gauge by the workmen.

The head and base flange contactor 2 is secured in a longitudinal slot 10 disposed in one end of the gauge stock 1, said contactor 2 having an upwardly extending main portion 5 formed with an outwardly bent hook 6, the lower edge of which is adapted to rest longitudinally upon the upper face of the rail head 20. The base of the contactor 2 is secured within the slot by means of nuts and bolts 14 and 15. The main portion of the contactor is cut away at 7 to provide for the U-shaped face plate 8 adapted to surround the stock at its end and fitted into recesses cut into the sides of the stock 1 adjacent the ends thereof, the plate being secured in place by means of the nuts and bolts 14 and 15. The manner of securing the contact member 2, heretofore described, assures a rigid and accurate connection of the same to the stock.

The outer edge of the U-shaped plate 8 of the stock presents a smooth vertical surface when contacting with the edge of the rail base flange 19.

The opposite end of the stock 1 supports the base flange contactor 3 in recessed portions 12 cut away from the bottom and end of the stock 1 so as to prevent any lateral displacement of the contact member 3 on the stock. The base flange contactor 3 is formed of an integral metal sheet which has preferably five fingers 9, 9, 10, 11 and 13 cut from the blank and adapted to be alternately bent upward and downward relative to each other in such a manner that the fingers 10, 11 and 13 bend downwardly at right angles to the main body of the contact 3 and the intermediate fingers 9 are bent upwardly at an angle corresponding to the angles of the upper face of the rail base flange 71. The upper side of the stock 1 is recessed to receive a plate 13 upon which the nuts and bolts 22 and 23 of the bolts bear to secure the base flange contactor 3 to the stock 1.

When it is desired to lay a section of track, one rail is secured in place upon a tie plate on the ties in any manner depending upon the type of ties that are used. For illustra-

tion I will assume that wooden ties are to be used together with the tie plates having inwardly inclined faces so that the head flanges 20 and 21 are canted inwardly. When the rails 17 have been placed on the ties, the base gauge is caused to rest the lateral projection 6 of the contactor 2, upon the upper face of the rail head 20 and at the same time the U-shaped face plate 8 is contacted with the edge of the rail flange 19. The stock 1 is held in horizontal position perpendicular to the rail 17 while the rail is brought into its approximate position on the tie plates. The contactor 3 will be engaged by the rail base flange 71 when the rail is moved towards the contactor 3. The turned down fingers 12, 10 and 18 will engage the inner edge of the base rail flange 21 while the fingers 11 and 13 will rest upon the upper inclined face thereof. The head rail is held in the position described while it is being secured to the tie in any well known manner. It will be seen from the above that any "settling" of the rails 17 or 71 is prevented in that the base of the rail has been properly gauged in place by my gauge. Heretofore the practice has been to gauge rails from the rail head flange which has proved entirely unsatisfactory on account of the rails settling out of alignment during the heavy usage to which they are subjected.

Referring now to Figs. 9 and 10 of the drawings wherein I have disclosed another embodiment of my invention of which 25 is designated as the stock or body of my gauge and which is preferably of wood and provided at each end with contact face plates 27 and 28. The ends of the stock 25 are preferably reduced at 24 and 26 by cutting away a portion thereof, so as to form upwardly and downwardly inclined surfaces. The downwardly inclined surfaces receive the inclined portions 29 of the contactors 27 and 28. Inasmuch as the contact plates 27 and 28 are identical in construction and may be attached to either end of the stock 1, in the same manner I will hereafter described one of the said plates which will be understood to apply to each of the contact plates 27 and 28. The contact plates 27 and 28 are preferably formed of an integral body of metal having the downwardly inclined base 29 which is secured to the bottom of the stock 25 preferably by means of the screws 31. The upright wall 31 of the contactors are secured to the extremity of the stock 1 by screws 32. Depending from the portions 29 of the contactors 27 and 28 and forming an integral part thereof, are the downward extensions 33 which are provided to engage the edges of the rail base flanges such as the flange 34 of a rail 36. The stock 25 may be provided with a handle 35 secured to the top side of the same, preferably intermediate the ends thereof.

Referring now to Figs. 6, 7 and 8 of the

drawings I have illustrated two other embodiment employing rail contactors which may be employed. The base flange contactor 40 illustrated in Figs. 6 and 7 comprises a forked body portion secured in any suitable manner to one end of the stock 41 and having the lower side 44 thereof inclined downwardly at 42 and terminating in an integral flange 43, adapted to contact with the edge and top of the rail base flange 45 of a rail 50. The forked ends 46 and 47 are spaced a substantial distance apart to effect desired alignment.

The rail and base flange contactor illustrated in Fig. 8 comprises an upwardly and outwardly extending contact portion 60, preferably made of sheet steel, the end 61 adapted to contact with the upper face of a rail 62. The lower end of the contact member 60 extends downwardly beyond the lower face of the stock 63 to form a depending projection 64 which is adapted to rest against the edge of the base flange 64 of a rail 62 in a manner shown in the drawings. The bottom of the stock 63 is formed with a grooved edge portion 66 adjacent its end which clears the base rail flange 65.

Each rail does not rest upon a single tie alone but on a large number of ties which in turn are embedded in the roadbed, which has been carefully levelled. Individual ties may vary in their upper surface to a slight extent, but when the rail is spiked to all of the ties upon which it rests, and particularly after the rails have been used by trains running over them, they will take such a position determined by the general level of all of the ties and the weight sustained by the rails.

If a gauge adapted to predetermine the distance between the rail heads was used and the ties spiked in place to maintain this distance, ultimately through use the rails may cant to their normal positions which may be vertical or which may be inclined if cradles are interposed between the tie and rail, which have sloping upper surfaces in order to give the rails the desired amount of cant. The rails will ultimately then be differently spaced than when the rails are originally placed.

Applicant's invention, however, provides for spacing of the rail bases; whereby even though, for instance, all of the spikes were driven on the inside of the rail to a greater extent than those on the outside, producing initial canting, that subsequently when "settling" has occurred and the rails take, as they ultimately and inevitably must do, their predetermined relation of canting depending upon the slope of surfaces upon which they rest, the spacing between the rail heads will be that which it should be with their bases spaced a predetermined distance apart.

It will be apparent that a gauge constructed as described will readily and accurately space the rails in parallel relation to each other without the probability of the rails sub-

quently settling out of parallel relation, and is adapted to the well known types of rails commonly in use.

My gauge can be manufactured at a small cost and be capable of withstanding exposure to the elements and rough usage without serious damage to the same.

Having thus described my invention in several embodiments, I am aware that numerous and extensive departures may be made from the embodiments herein illustrated and described but without departing from the spirit of my invention.

What I claim is:—

- 15 1. A track gauge comprising a spacer bar adapted to be disposed between a pair of railway rails, a plurality of rail contactor elements for the bar carried at ends thereof and adapted to make simultaneous contact with both rails of the track, one of said elements adapted to rest upon the top surface of the rail head, a second contactor element at the same end of the bar relatively so disposed as to contact at its outer edge with the inner edge of the base flange of the rail upon whose head the first element rests, a third contactor element at the other end of the bar disposed to contact with the rail base flange of the companion rail of the track.
- 20 2. A track gauge comprising a spacer bar adapted to be disposed between a pair of railway rails, a plurality of rail contactor elements for the bar carried at ends thereof and adapted to make simultaneous contact with both rails of the track, one of said elements adapted to rest upon the top surface of the rail head, a second contactor element at the same end of the bar relatively so disposed as to contact at its outer edge with the inner edge of the base flange of the rail upon whose head the first element rests, a third contactor element at the other end of the bar disposed to contact with the rail base flange of the companion rail of the track.
- 25 3. A track gauge comprising a spacer bar adapted to be disposed between a pair of railway rails, a plurality of rail contactor elements for the bar carried at ends thereof and adapted to make simultaneous contact with both rails of the track, one of said elements adapted to rest upon the top surface of the rail head, a second contactor element at the same end of the bar relatively so disposed as to contact at its outer edge with the inner edge of the base flange of the rail upon whose head the first element rests, a third contactor element at the other end of the bar disposed to contact with the rail base flange of the companion rail of the track.
- 30 4. A track gauge comprising a spacer bar adapted to be disposed between a pair of railway rails, a plurality of rail contactor elements for the bar carried at ends thereof and adapted to make simultaneous contact with both rails of the track, one of said elements adapted to rest upon the top surface of the rail head, a second contactor element at the same end of the bar relatively so disposed as to contact at its outer edge with the inner edge of the base flange of the rail upon whose head the first element rests, a third contactor element at the other end of the bar disposed to contact with the rail base flange of the companion rail of the track.
- 35 5. A track gauge comprising a spacer bar adapted to be disposed between a pair of railway rails, a plurality of rail contactor elements for the bar carried at ends thereof and adapted to make simultaneous contact with both rails of the track, one of said elements adapted to rest upon the top surface of the rail head, a second contactor element at the same end of the bar relatively so disposed as to contact at its outer edge with the inner edge of the base flange of the rail upon whose head the first element rests, a third contactor element at the other end of the bar disposed to contact with the rail base flange of the companion rail of the track.
- 40 6. A track gauge comprising a spacer bar adapted to be disposed between a pair of railway rails, a plurality of rail contactor elements for the bar carried at ends thereof and adapted to make simultaneous contact with both rails of the track, one of said elements adapted to rest upon the top surface of the rail head, a second contactor element at the same end of the bar relatively so disposed as to contact at its outer edge with the inner edge of the base flange of the rail upon whose head the first element rests, a third contactor element at the other end of the bar disposed to contact with the rail base flange of the companion rail of the track.
- 45 7. A track gauge comprising a spacer bar adapted to be disposed between a pair of railway rails, a plurality of rail contactor elements for the bar carried at ends thereof and adapted to make simultaneous contact with both rails of the track, one of said elements adapted to rest upon the top surface of the rail head, a second contactor element at the same end of the bar relatively so disposed as to contact at its outer edge with the inner edge of the base flange of the rail upon whose head the first element rests, a third contactor element at the other end of the bar disposed to contact with the rail base flange of the companion rail of the track.
- 50 8. A track gauge comprising a spacer bar adapted to be disposed between a pair of railway rails, a plurality of rail contactor elements for the bar carried at ends thereof and adapted to make simultaneous contact with both rails of the track, one of said elements adapted to rest upon the top surface of the rail head, a second contactor element at the same end of the bar relatively so disposed as to contact at its outer edge with the inner edge of the base flange of the rail upon whose head the first element rests, a third contactor element at the other end of the bar disposed to contact with the rail base flange of the companion rail of the track.
- 55 9. A track gauge comprising a spacer bar adapted to be disposed between a pair of railway rails, a plurality of rail contactor elements for the bar carried at ends thereof and adapted to make simultaneous contact with both rails of the track, one of said elements adapted to rest upon the top surface of the rail head, a second contactor element at the same end of the bar relatively so disposed as to contact at its outer edge with the inner edge of the base flange of the rail upon whose head the first element rests, a third contactor element at the other end of the bar disposed to contact with the rail base flange of the companion rail of the track.

posed as to contact at its outer edge with the inner edge of the base flange of the rail upon whose head the first element rests, a third contactor element at the other end of the bar disposed to contact with the rail base flange of the companion rail of the track, said first and said second contactor elements comprising rail contacting surfaces disposed at right angles to each other, said third contactor having its rail contacting surfaces disposed in a plane parallel to the contacting surface of the said second contactor element.

4. A track gauge comprising a spacer bar adapted to be disposed between a pair of railway rails, a plurality of rail contactor elements for the bar carried at ends thereof and adapted to make simultaneous contact with both rails of the track, one of said elements adapted to rest upon the top surface of the rail head, a second contactor element at the same end of the bar relatively so disposed as to contact at its outer edge with the inner edge of the base flange of the rail upon whose head the first element rests, a third contactor element at the other end of the bar disposed to contact with the rail base flange of the companion rail of the track, said first and said second contactor elements comprising rail contacting surfaces disposed at right angles to each other, said third contactor having its rail contacting surfaces disposed in a plane parallel to the contacting surface of the said second contactor element, said bar having an outwardly directed extension from the said other end adapted to rest upon the upper surface of the adjacent rail base flange.

5. A track gauge comprising a spacer bar adapted to be disposed between a pair of railway rails, and a plurality of rail contactor elements for the bar carried at ends thereof and adapted to make simultaneous contact with both rails of the track, one of said elements adapted to contact with the inner edge of the rail base flange, a second contact element at the opposite end of the bar relatively so disposed as to contact at its outer edge with the inner edge of the base flange of the companion rail, a third contactor element at the same end of the bar adjacent the second element disposed to contact with the upper surface of the rail base flange of the rail of the track.

In testimony whereof I hereunto affix my signature this 16th day of March, 1926.

ROBERT EMMET KEOUGH.
